H. F. TAYLOR.
 ROTARY SPRINKLER THERMOSTATIC FIRE EXTINGUISHER.
 APPLICATION FILED MAY 2, 1916.

1,241,450.

Patented Sept. 25, 1917.

UNITED STATES PATENT OFFICE.

HAROLD FLETCHER TAYLOR, OF LOS ANGELES, CALIFORNIA, ASSIGNEE OF FIFTY-ONE ONE-HUNDREDTHS TO JOSEPH MESMER, OF LOS ANGELES, CALIFORNIA.

ROTARY-SPRINKLER THERMOSTATIC FIRE-EXTINGUISHER.

1,241,450.

Specification of Letters Patent. Patented Sept. 25, 1917.

Application filed May 2, 1916. Serial No. 94,996.

To all whom it may concern:

Be it known that I, HAROLD FLETCHER TAYLOR, a citizen of the United States, residing at Los Angeles, in the county of Los Angeles and State of California, have invented a new and useful Rotary-Sprinkler Thermostatic Fire-Extinguisher, of which the following is a specification.

An object of this invention is to make provision for applying a fire-extinguishing fluid to an incipient or other conflagration within a building or other confined space.

The fluid for this purpose may be a carbon tetra-chlorid or tri-carbo or any liquid chlorin derivative that will produce chlorin gas sufficient to destroy carbon combustion in the confined space, and which will then prevent combustion of carbon with oxygen and fire.

An object of this invention is to provide means whereby a moderate isolated supply of the anti-combustion liquid may be stored and may be discharged throughout a predetermined space to produce a gas for smothering fire confined between walls inclosing said space.

The accompanying drawings illustrate the invention.

Figure 1 is an elevation partly in section and partly diagrammatic of apparatus constructed in accordance with this invention.

Fig. 2 is a plan section of the rose nozzle on line indicated at α^2 , Fig. 1.

The supply tank 1 may be variously constructed and may be provided with an external or internal insulation to maintain an even temperature of the contents of the tank. Internal insulation 2 is indicated in Fig. 1. In case the tank 1 is wooden said insulation may be of cork or other suitable material cemented or otherwise fastened to the wooden walls by any suitable means.

Said tank may be filled through a nipple 3 and afterward closed by a plug or cap 4.

An outlet pipe 5 controlled by the automatically closed valve 6 leads from the bottom of the tank and is connected to a vertical pipe 7 forming the tubular stem of a rotary sprinkling device as the sprinkler head 8. Said tubular stem discharges into the rotary sprinkler device 8. Said device may be of any suitable form, but is shown as a rose nozzle sprinkler head with perforations 9, 10 and 11 at its under side, top side and periphery, so that when the sprin-

kler device is rotated rapidly the liquid contents thereof supplied to it from the pipe 7 will be thrown out through the outlets by centrifugal force. To assist in this effect the bottom 9 and walls of the circular nozzle 8 may be provided with impellers such as the upward projections α .

The sprinkler 8 may be of any suitable character and may be rotated by any suitable means, such as a spring motor, a water motor or an electric motor. For convenience of illustration, an electric motor 12 is shown connected by a train 13 of gearing to drive the tubular stem 7 of the sprinkler head or nozzle 8 into which liquid from the supply tank will be inducted. When the valve 6 is open there is provided a free passage into pipe 5.

It may be desirable to shut off the liquid supply between the pipe 5 and the top of tube 7 and with this object in view a governor valve 14 controlled by suitable means is provided.

In order that said governor valve may only open when the sprinkler head 8 has attained sufficiently high speed to generate the required centrifugal force to properly distribute the liquid, a centrifugal governor 15 of any suitable construction is connected to be rotated simultaneously with the sprinkler head 8, so that when the head is rotating at a required speed the valve will be held open, but will otherwise be closed.

Thermosat - controlled electro - magnetic means are provided for setting the sprinkler into operation. With this object in view an electric circuit comprising a lead 16 connected to a thermostatic switch 17, and through such switch with the lead 18 serves current to drive the motor 12 from the power main p whenever the circuit is completed through the switch 17. Leads 19 to electro-magnet 20 of the valve 6 will open said valve simultaneously with the starting of the motor.

The thermostatic switch 17, therefore controls the supply valve 6 and the motor.

Any thermostatically operated means may be employed to open the valve 6 and to set the motor into operation, so that whenever heat is applied to the thermostatic means as by heat rising to the ceiling at 17, the circuit will be closed and the electro-magnetic valve 6 will be opened and the motor 12 put into operation, thereby rotating the sprinkler 116

head and operating the governor 15 to open the valve 14 so as to allow liquid to flow to the sprinkler head, whence it will be distributed by centrifugal force over a wide 5 area.

It is intended that the liquid shall be of a character to expand into a heavy combustion-preventing gas or vapor when discharged into the open air, so as to sink to 10 exclude oxygen from the fire that produced the heat that operated the thermostatic switch 17.

The supply tank 1 is provided with an air vent 22 that is normally closed by an automatically closed valve 23 controlled by electro-magnetic means, similar to that of valve 6, said means being energized through the leads 21 so that when the valve 6 is opened, the valve 23 will also be opened, and vice 15 versa, so that liquid may flow from the tank when required, but the valve 23 will prevent evaporation from the tank when the liquid is at rest.

The pipe 5 is connected with sprinkler 25 stem 7 by a hollow box 24 in which the upper end of the pipe 7 is journaled to rotate.

The governor valve 14 may be variously constructed and arranged, and in the instance shown is of a cylindrical type having 30 ports *d* adapted to slide into register with ports *e* of the valve chamber 25, and thus open communication from the pipe 5 to the stem 7. The valve controlling governor 15 is connected with the sprinkler stem 35 through gearing 26 to rotate the governor according to the speed of the sprinkler; and the valve 14 is operatively connected with said governor through valve stem 27 and lever 28 which lever engages with a 40 slidable sleeve 29 adapted to be raised and lowered by the governor balls 30 in accordance with the speed of the same.

The governor balls thus actuate the valve to open and close communication through 45 the ports *d* and *e* in accordance with the speed of the sprinkler.

In practical operation when a fire occurs in a room or inclosure provided with this installation, the heat from said fire arising 50 to the ceiling *c* reaches the thermostatic switch 17, closes the contact for supplying electric energy to the motor and to the electro-magnets that open the valves 6 and 23. The liquid flowing through pipe 5 enters the 55 pipe 7 as soon as the sprinkler has reached the desired speed whereupon the governor 15 will operate the valve 14 and liquid

will be allowed to flow into the nozzle, from whence it is distributed by centrifugal force.

When the fire is extinguished and the 60 thermostat cools down, the current is turned off from the motor and the valves 14, 6 and 23 will all automatically close and the apparatus will be ready for further action in case another fire occurs.

65

I claim:

1. A fire extinguisher comprising a tank, a rotary sprinkler on a lower level than the tank, a pipe line connecting the sprinkler to the tank, a thermostatically controlled electro-magnetic valve in the pipe line, a motor for operating the sprinkler, and a governor for regulating the flow of water to the sprinkler.

70

2. A fire extinguisher comprising a rotary 75 sprinkler head, a motor to rotate the sprinkler head, means to supply liquid to the sprinkler head, valve means to control said supply means, thermostatic means to control the valve means and the motor; a governor 80 valve to control the supply of liquid to the sprinkler, and governor means to control the governor valve.

85

3. A fire extinguisher comprising a rotary sprinkler, a motor to rotate the sprinkler, 90 means to supply liquid to the sprinkler, valve means to control said supply means, thermostatic means to control the valve means and the motor, a governor valve to control the supply of liquid to the sprinkler, 95 and governor means operated by the motor to control the governor valve.

4. A fire extinguisher comprising a tank, a rotary sprinkler on a lower level than the tank, a pipe line connecting the sprinkler to 95 the tank, a thermostatically controlled valve in the pipe line, a thermostatically controlled vent in the tank, and a governor for regulating the flow of water to the sprinkler.

5. A fire extinguisher comprising a tank, 100 a thermostatically controlled vent for the tank, an outlet pipe for the tank, an electro-magnetic valve in the outlet pipe, a thermostat for controlling the valve, a rotary sprinkler to receive the flow of water from 105 the tank through the pipe, a motor for rotating the sprinkler, and a governor for regulating the flow.

In testimony whereof, I have hereunto set my hand at Los Angeles, California, this 110 22d day of April 1916.

HAROLD FLETCHER TAYLOR.

Witness:

JAMES R. TOWNSEND.
